UNITED STATES PATENT OFFICE

160,644

MOVING FIGURE WHEELED TOY

Harry C. Marsh, Memphis, Tenn.

Application November 19, 1948, Serial No. 149,707

Term of patent 7 years

(Cl. D34—15)

To all whom it may concern:

Be it known that I, Harry C. Marsh, a citizen of the United States, residing at Memphis, in the county of Shelby and State of Tennessee, have invented a new, original, and ornamental Design for a Moving Figure Wheeled Toy, of which the following is a specification, reference being had to the accompanying drawing, forming part thereof.

Figure 1 is a perspective view of the moving figure wheeled toy, showing my new design; and Figure 2 is a front view thereof.

The figure is shaded to show color contrast, the opposite side of the figure being substantially the same in appearance as the side shown in Figure 1.

I claim:

The ornamental design for a moving figure wheeled toy, as shown.

HARRY C. MARSH.
